(57) CLAIM

The ornamental design for zippered bag, as shown and described.

DESCRIPTION

FIG. 1 is a perspective view of a zippered bag according to the present invention;

FIG. 2 is a top view of the zippered bag of FIG. 1;
FIG. 3 is a first side view of the zippered bag of FIG. 1;
FIG. 4 is a second side view, rotated ninety degrees from the first side view, of the zippered bag of FIG. 1; and,
FIG. 5 is a third side view, opposite the second side view, of the zippered bag of FIG. 1.
